UNITED STATES PATENT OFFICE.

HARRY H. SCHROYER, OF CHICAGO, ILLINOIS, ASSIGNOR TO DUNBAR MANUFACTURING COMPANY, A CORPORATION OF ILLINOIS.

CAR-VESTIBULE DIAPHRAGM.

1,256,050.

Specification of Letters Patent. Patented Feb. 12, 1918.

Application filed September 10, 1915. Serial No. 49,978.

To all whom it may concern:

Be it known that I, HARRY H. SCHROYER, a citizen of the United States, and a resident of the city of Chicago, in the county of 5 Cook and State of Illinois, have invented certain new and useful Improvements in Car-Vestibule Diaphragms; and I do hereby declare that the following is a full, clear, and exact description of the same, reference 10 being had to the accompanying drawings, and to the numerals of reference marked thereon, which form a part of this specification.

This invention relates to an improved 15 type of vestibule diaphragm extremely simple in construction and operation, involving the use of few parts and cheap to manufacture and install.

It is an object therefore of this invention 20 to construct an improved type of diaphragm wherein a pair of rigid frame bars are utilized, one connected to the face plate of the diaphragm and the other to the end of the car, said bars connected to one another 25 by suitable heavy flexible fabric or composition material to permit relative movement therebetween and yet insuring the interior of the diaphragm remaining weatherproof.

It is also an object of this invention to 30 construct a vestibule diaphragm wherein continuous metallic members are provided extending around the top and sides of the diaphragm and suitably connected together by a single flexible connection.

It is furthermore an important object of 35 this invention to construct a vestibule diaphragm embodying the use of continuous bars forming the top and side members of the diaphragm suitably connected together 40 by a strip of heavy ply fabric or the like to permit movement of said respective bars into or away from one another according to the conditions imposed upon the diaphragm.

It is finally an object of this invention to 45 construct a vestibule diaphragm simple in construction and operation and well adapted for the purposes designed.

The invention (in a preferred form) is 50 illustrated in the drawings and hereinafter more fully described.

In the drawings:

Figure 1 is an interior sectional elevation

of a vestibule diaphragm embodying the principles of my invention. 55

Fig. 2 is a section taken on line 2—2 of Fig. 1.

Fig. 3 is an enlarged detail section taken on line 3—3 of Fig. 1.

Fig. 4 is an enlarged detail section taken 60 on line 4—4 of Fig. 1.

Fig. 5 is a view similar to Fig. 4, of a modified form of device.

Fig. 6 is a sectional detail view thereof 65 at the upper end of the structure.

Fig. 7 is a view similar to Fig. 5, of another modified form of device.

Fig. 8 is a view thereof similar to Fig. 6.

As shown in the drawings, the reference 70 numeral 1, indicates the end of a car, and 2, the extensible vestibule platform thereof, and the reference numeral 3, denotes as a 75 whole the face plate of the diaphragm, which is adapted to abut against a similar face plate of another vestibule diaphragm on another car. Rigidly secured in any suitable manner by bolts or otherwise upon the end of the car is an outwardly directed continuous channel frame member 4, forming a part 80 of the legs or sides and top of the vestibule diaphragm, and secured upon the inner surface of the face plate 3, is a continuous Z-bar 5, which likewise extends upwardly to form the legs or sides of the diaphragm and across the top to form a part thereof. 85

Secured in any suitable manner by means of rivets, bolts or otherwise on the inner surface of one of the flanges of the Z-bar 5, is one margin of a flexible heavy fabric or other material strip 6, the other margin of 90 which is secured upon the outer surface of one of the flanges of the channel member 4, said strip extending upwardly along the sides and across the top of the diaphragm and consisting substantially of three parts, 95 two of which form the legs and the other the top of the diaphragm, said leg sections being joined to the top portion by means of sector shaped shoulder pieces 7, stitched thereto. As will be readily seen from the 100 construction shown, the width and height of the Z-bar frame member 5, is greater than that of the channel frame member 4, thus permitting the channel member 4, to telescope within the Z-bar member 5, when the 105 diaphragm is contracted. Of course due to

the heavy fabric flexible connection 6, the diaphragm may be warped into practically any position such as required when in use by the cars traveling on uneven track or in 5 rounding curves.

In the modified form of device illustrated in Figs. 5 and 6, I have shown a continuous plate or bar 8, having one margin turned substantially at a right angle for attachment 10 to the end of the car 1, and another similar continuous plate or bar 9, connected to the face plate 3, of the diaphragm with a strip of flexible fabric 10, substantially of U-shape connected at its margins thereto.

15 In the modified form of device illustrated in Figs. 7 and 8, I have shown a construction wherein continuous bars are used secured on the car end and face plate respectively, the one denoted by the reference numeral 11, substantially of channel section and having an inturned margin on which the margin of a flexible strip 12, is attached, and the other bar 13, substantially of S-shape section and provided with an inturned 20 margin to which the other margin of the strip 12, is attached.

I am aware that various details of construction may be varied through a wide range without departing from the principles 30 of this invention, and I therefore do not purpose limiting the patent granted otherwise than necessitated by the prior art.

I claim as my invention:

1. A vestibule diaphragm comprising a 35 channel-bar frame member adapted for attachment on the end of a car, a Z-bar frame member of greater width and height than said channel member adapted for attachment on the face plate of the diaphragm 40 permitting the channel bar to telescope therewithin, and a flexible connection between said channel bar and said Z-bar frame members.

2. In a vestibule diaphragm the combina-

tion with the face plate and end of the car 45 of metallic frame members, secured to each adapted to telescope within one another and a flexible connection of U-shape having its ends rigidly secured to the frame members.

3. In a vestibule diaphragm in combination with the car and face plate, of a continuous frame member of channel section secured upon the car and a continuous frame member of the Z-section secured upon said face plate, said members extending upwardly to 50 form the sides and top of the diaphragm and adapted to telescope one within the other, and a weatherproof flexible connection secured to said respective frame members to permit relative movement thereof and effect a sealing connection therebetween.

4. In a device of the class described interfitting metallic frame members forming the legs and top, sector shaped metallic shoulder pieces connecting the same and a flexible 65 member bent in substantially U-shape and having opposite ends rigidly attached to the metallic frame members and shoulder pieces.

5. A vestibule diaphragm of the class described comprising frame members forming 70 the legs and top of a diaphragm, flanges formed on the adjacent ends of each thereof, and a continuous flexible connection along the legs and top of the diaphragm between said members attached to the flanges thereof. 75

6. In a vestibule diaphragm of the class described, a pair of flanged frame members of different width and height adapting one to move within the other, and a flexible sealing connection between said members having 80 both ends rigidly secured to the members.

In testimony whereof I have hereunto subscribed by name in the presence of two subscribing witnesses.

HARRY H. SCHROYER.
